DESIGN FOR A MIXER

James L. Andrews, Birmingham, Ala.

Application November 23, 1934, Serial No. 54,135

Term of patent 14 years

To all whom it may concern:

Be it known that I, James L. Andrews, a citizen of the United States, residing at 1427 North 33rd Street, in the city of Birmingham, county of Jefferson, and State of Alabama, have invented a new, original, and ornamental Design for Mixers, of which the following is a specification, reference being had to the accompanying drawing, forming part thereof.

The figure is a perspective view of a mixer, showing my new design.

I claim:

The ornamental design for a mixer, as shown.

JAMES L. ANDREWS.
